UNITED STATES PATENT OFFICE.

JONATHAN E. GOOD, OF DIDSBURY, ALBERTA, CANADA.

CULVERT-HEAD OR RETAINING-WALL FOR CULVERTS.

1,228,662.

Specification of Letters Patent.

Patented June 5, 1917.

Application filed January 8, 1916. Serial No. 71,182.

To all whom it may concern:

Be it known that I, JONATHAN R. GOOD, a citizen of the Dominion of Canada, residing at the town of Didsbury, in the Province of Alberta, in the Dominion of Canada, have invented new and useful Improvements in Culvert-Heads or Retaining-Walls for Culverts; of which the following is a specification.

10 This invention relates to culvert heads or retaining walls for culverts and the primary object of this invention is to provide culvert heads or retaining walls which may be attached to (and detached from) metal pipes 15 in culverts (for the conduction of water) which will act as retaining walls and prevent water, frost and other agents from displacing the earth, rock and other loose materials from around the ends of the conductor pipe 20 upon which they are attached, and thus act as retaining walls and take the place of stationary and permanent walls constructed of concrete, stone and similar materials. In describing the invention in detail, reference 25 will be had to the accompanying drawings in which similar letters refer to similar parts throughout the several views and in which:

Figure 1, is a side view of a section of an ordinary corrugated metal conductor pipe 30 commonly used in the construction of culverts, with the culvert head constructed in accordance with this invention attached thereto.

Fig. 2, is an end view of the culvert head 35 constructed in accordance with this invention.

Fig. 3, is a side view of the culvert head constructed in accordance with this invention detached from the conductor pipe.

40 Fig. 4 is an end view of a metal ring used to attach the culvert head supports to the conductor pipe.

Referring more particularly to the drawings A designates four pieces of corrugated sheet metal rigidly riveted together forming a hollow truncated pyramid or funnel shaped structure (having corrugations running parallel to the base) with square base and having a comparatively short axis at 45 right angles to the base. P is a square piece of sheet metal riveted at its outward edges to the smaller end of the funnel shaped structure A, and having a centrally located circular opening approximating in diameter the 50 diameter of the end of B which is a corrugated metal conductor pipe ordinarily used

in the construction of culverts. R is a short piece of cylindrical corrugated sheet metal pipe having the edges of one end bent outward at right angles and riveted to the end 60 edge of the circular opening in P, the outer circumference of R being slightly less than the inner circumference of B so that R will fit inside of B tightly. At H, I, J and K are metal rings riveted to A into which are 65 hooked supporting metal rods D, E, F and G. C is a circular metal ring approximating in size the outer circumference of the conductor pipe B. Attached by bolts to the ring C at L, M, N and O are the rods D, E, F and 70 G. The size of the entire structure is regulated only by size of the conductor pipe B.

The culvert head is attached to the corrugated metal conductor pipe B as follows: The cylindrical corrugated metal tube R is 75 fitted into the end of the conductor pipe B so that the metal sheet P is in contact with the end of B. The metal rods D, E, F and G are hooked into the metal rings at I, H, J and K respectively and the said rods are 80 bolted into the metal ring C. The metal ring C is placed around the corrugated metal conductor pipe B by drawing the bolt S. The metal rods, D, E, F and G are then 85 drawn tight by tightening the nuts at M, N, L and O.

In the construction of a culvert the conductor pipe is then laid with a culvert head attached as above set forth at either end or with a culvert head at both ends of the conductor pipe B. The earth and other road materials are then packed in over the conductor pipe B and against the inner surfaces of the culvert heads. The culvert heads will thus act as a retaining wall holding the earth 90 and other road materials in place and preventing them being washed away by water or displaced by frost or other causes. If required the culvert head may be detached at any time without injury.

What I do claim as my invention and desire to secure by Letters Patent is:

1. The combination with a metal conductor pipe for culverts of a culvert head or retaining wall constructed of four quadrilateral pieces of corrugated sheet metal riveted together so as to form a hollow truncated pyramid or funnel shaped structure with rectangular base (the corrugations running parallel to the base) and having a comparatively short axis with a rectangular piece of sheet metal at the apex of the structure, the 100

2
said rectangular piece of sheet metal having a centrally located opening of the same size and shape as the end of the conductor pipe with a short piece of corrugated pipe approximating in size the size of the opening in the said rectangular piece of sheet metal and being slightly smaller than and of the same shape as the conductor pipe and having the edges of one end bent outward at 10 right angles and riveted to the said rectangular piece of sheet metal around the edge of the opening on the opposite side to that on which is riveted the funnel shaped structure so that axis of the said piece of pipe is at 15 right angles to the base of the pyramid and fitted into the culvert conductor pipe so that the end of the culvert conductor pipe comes in contact with the rectangular piece of sheet metal; and with a corrugated metal band 20 bound around the short piece of corrugated pipe with draw bolts binding it to the conductor pipe, with four metal rods hooked into metal rings riveted to the outer basal edge of the pyramid, a metal ring firmly drawn around the conductor pipe by a bolt and nut into which are 25 bolted the outer ends of the said rods.

2. The combination with a conductor pipe for culverts of a culvert head or retaining wall constructed of four quadrilateral pieces of sheet metal riveted together so as to form a hollow truncated pyramid or funnel 30 shaped structure with rectangular base with a rectangular piece of sheet metal at the apex of the structure the said rectangular piece of sheet metal having a centrally located opening approximating in size and 35 shape the size and shape of the end of the said conductor pipe a short piece of metal piping being slightly smaller than and of the same shape as the conductor pipe and having the edges of one end bent upward at 40 45 right angles and riveted to the said rectangular

gular piece of sheet metal around the edge of the opening on the opposite side to that on which is riveted the funnel shaped structure so that the axis of the said piece of pipe is at an angle to the base of the pyramid and fitted into the culvert conductor pipe so that the end of the culvert conductor pipe comes in contact with the rectangular piece of sheet metal and with a metal band bound around the short piece of pipe with draw bolts binding it to the conductor pipe, with four metal rods hooked into metal rings riveted to the outer basal edge of the pyramid, a metal ring firmly drawn around the conductor pipe by a bolt and nut into which are bolted the outer ends of the said rods.

3. The combination with a metal conductor pipe of a hollow truncated pyramid or funnel shaped structure having a comparatively short axis with a piece of sheet metal completely covering and fastened to the apex of the said truncated pyramid, having a centrally located opening in it of the same shape and size as the end of the conductor pipe with a short piece of pipe approximating in size the size of the opening in the said piece of sheet metal and being slightly smaller than, and of the same shape as the conductor pipe, the said short piece of pipe being fastened to the said piece of sheet metal covering the apex of the said truncated pyramid and with a metal band drawn around the said short piece of pipe with draw bolts, the whole structure being held to the conductor pipe by four metal rods or chains hooked into metal rings fastened to the outer basal edge of the said pyramid, the outer ends of the said rods or chains being fastened to a metal ring or rod firmly drawn around the conductor pipe.

Didsbury, December 24th, 1915.
JONATHAN R. GOOD.
